(57) **ABSTRACT**

A lighting circuit controls lighting/extinguishing of a light source. A driving circuit generates a driving current which is to be supplied to the light source. A clamp circuit clamps a voltage between both ends of the light source to a clamp level in a period in which the light source is to be turned off. The clamp level is defined to be higher than zero and lower than a critical pressure when the light source is turned on/off.

LIGHTING CIRCUIT AND VEHICULAR LAMP

CROSS-REFERENCE TO RELATED APPLICATIONS

This application is based on and claims priority from Japanese Patent Application Nos. 2016-241472 and 2017-080809, filed on Dec. 13, 2016 and Apr. 14, 2017, with the Japan Patent Office, the disclosures of which are incorporated herein in their entireties by reference.

TECHNICAL FIELD

The present disclosure relates to a lamp used for, for example, a vehicle.

BACKGROUND

Light sources such as laser diodes (LD) and light emitting diodes (LED) are used for various applications such as vehicular lamps, projectors, backlights of liquid crystal panels, illumination devices, and optical communication technologies.

FIG. 1 is a circuit diagram of a lighting circuit in the related art. The lighting circuit 1100 includes a driving circuit 1102 and a bypass switch 1104. The driving circuit 1102 supplies a driving current I_{DRV} which is stabilized in a predetermined amount to a light source 1002. The bypass switch 1104 is connected in parallel with the light source 1002.

When the bypass switch 1104 is turned off, since the driving current I_{DRV} flows to the light source 1002, the light source 1002 emits light. When the bypass switch 1104 is turned on, since the driving current I_{DRV} flows to the light source 1104, the light source 1002 is turned off. Therefore, lighting/extinguishing of the light source 1002 may be switched by switching the bypass switch 1104. See, for example,

SUMMARY

For example, when a light source is used as a vehicular lamp or a backlight, dimming of the light source becomes possible by switching the light source 1002 to a frequency that the human eye cannot perceive and changing the duty ratio. The switching frequency used for general pulse width modulation (PWM) dimming is in the order of several tens to several hundreds of Hz, which may be implemented in the lighting circuit 1100 of FIG. 1.

However, it is difficult to switch the light source 1002 at a frequency higher than several kHz in the lighting circuit 1100 of FIG. 1.

The present disclosure has been made under the above-described circumstances and one of exemplary embodiments thereof provides a lighting circuit that is capable of switching a light source at high speed.

A certain aspect of the present disclosure relates to a lighting circuit of a light source. The lighting circuit includes: a driving circuit configured to generate a driving current to be supplied to the light source; and a clamp circuit configured to clamp a voltage between both ends of the light source to a clamp level which is defined to be higher than zero and lower than a critical pressure when the light source is turned on/off in a period in which the light source is to be turned off.

2

The voltage between both ends of the light source in the lighting period is V_{ON} , and the clamp level is V_{CL} . In this aspect, since the voltage between the both ends is clamped to the clamp level V_{CL} in the extinguishing period of the light source, the variation width ΔV of the voltage of the both ends equals to $V_{ON}-V_{CL}$ when switching from off to on. By moving the V_{CL} closer to a threshold voltage V_{TH} of the turning-on/off of the light source, the variation width ΔV when switching from off to on may be reduced. Thus, the light source may be turned on for a short period of time. In addition, since the load fluctuation when viewed from the driving circuit may be reduced, restrictions on the design of the driving circuit may be alleviated.

15 The clamp circuit may immediately reduce the voltage between the both ends of the light source to substantially zero in response to an extinguishing instruction of the light source and then clamp the voltage to the clamp level. As a result, after the extinguishing instruction of the light source, 20 the light source may be turned off for a short period of time.

The clamp circuit may include a first switch and a clamp resistor provided in series on a first path in parallel with the light source. When a resistance value of the first path is R_1 , a threshold voltage of the light source is V_{TH} , and the driving 25 current is I_{DRV} , a relation of $0 < R_1 \times I_{DRV} < V_{TH}$ may be satisfied.

The clamp circuit may include the first switch provided on the first path that is in parallel with the light source. When the resistance value of the first path is R_1 , a threshold voltage 30 of the light source is V_{TH} , and the driving current is I_{DRV} , a relation of $0 < R_1 \times I_{DRV} < V_{TH}$ is satisfied.

The clamp circuit may further include a second switch provided on a second path that is in parallel with the light source. The second switch may be turned on immediately 35 after an extinguishing instruction of the light source, and may be turned off before a lighting instruction of the light source. As a result, switching from on to off may be performed at high speed.

The clamp circuit may include: a shaft transistor provided 40 between the both ends of the light source; and a transistor control circuit configured to generate a voltage of a control terminal of the shaft transistor such that a voltage between the both ends of the light source becomes the clamp level in a period in which the light source is to be turned off.

45 The transistor control circuit may include a feedback circuit which brings the voltage between the both ends of the light source close to the clamp level by feedback. The voltage between the both ends of the light source may be clamped by configuring a so-called shaft regulator with the feedback circuit and the shaft transistor.

The transistor control circuit may also include a constant voltage circuit provided between the control terminal of the shaft transistor and a high potential side end.

The transistor control circuit may further include a third 55 switch provided between the control terminal of the shaft transistor and a low potential side end of the light source, or between the control terminal of the shaft transistor and a low voltage terminal to which a predetermined low voltage is supplied. By turning on the third switch, the shaft transistor 60 may be turned off (or turned on) immediately and the light source may be turned on/off instantaneously.

The transistor control circuit may further include a fourth 65 switch provided between the control terminal of the shaft transistor and a high potential side end of the light source, or between the control terminal of the shaft transistor and a high voltage terminal to which a predetermined high voltage is supplied. By turning on the fourth switch, the shaft

transistor may be turned on (or turned off) immediately and the light source may be turned on/off instantaneously.

Another aspect of the present disclosure relates to a vehicular lamp. The vehicular lamp may include a light source and any one of the lighting circuits that drive the light source as described above.

Further, any combination of the above-described components or replacement of the components or expressions of the present disclosure among, for example, a method, a device, and a system is also effective as an aspect of the present disclosure.

In addition, the description of this section does not explain all the features which are essential for the present disclosure, and therefore, the sub-combinations of the described features may also be included in the present disclosure.

According to a certain aspect of the present disclosure, a light source may be switched at high speed.

The foregoing summary is illustrative only and is not intended to be in any way limiting. In addition to the illustrative aspects, embodiments, and features described above, further aspects, embodiments, and features will become apparent by reference to the drawings and the following detailed description.

BRIEF DESCRIPTION OF THE DRAWINGS

FIG. 1 is a circuit diagram of a lighting circuit in the related art.

FIG. 2 is a block diagram of an illumination device including a lighting circuit according to an exemplary embodiment.

FIG. 3 is a view illustrating I/V characteristics of a light source.

FIG. 4 is an operation waveform diagram of the lighting circuit of FIG. 2.

FIG. 5 is an operation waveform diagram of the lighting circuit of FIG. 1.

FIG. 6 is an operation waveform diagram of the lighting circuit including a second function.

FIG. 7 is a circuit diagram of a first configuration example of the lighting circuit of FIG. 2.

FIG. 8 is a circuit diagram of a second configuration example of the lighting circuit of FIG. 2.

FIGS. 9A and 9B are circuit diagrams illustrating a specific configuration example of a clamp circuit of FIG. 8.

FIGS. 10A to 10E are circuit diagrams illustrating modifications of the clamp circuit.

FIG. 11 is a circuit diagram of a third configuration example of the lighting circuit of FIG. 2.

FIG. 12 is a circuit diagram illustrating a first configuration example of a clamp circuit of FIG. 11.

FIG. 13 is an operation waveform diagram of the clamp circuit of FIG. 12.

FIG. 14 is a circuit diagram illustrating a second configuration example of the clamp circuit of FIG. 11.

FIGS. 15A to 15D are views illustrating a vehicular lamp including a lighting circuit.

FIGS. 16A and 16B are circuit diagrams including a lighting circuit.

FIG. 17 is a block diagram of an illumination device including a plurality of light sources.

DETAILED DESCRIPTION

In the following detailed description, reference is made to the accompanying drawings, which form a part hereof. The illustrative embodiments described in the detailed descrip-

tion, drawings, and claims are not meant to be limiting. Other embodiments may be utilized, and other changes may be made, without departing from the spirit or scope of the subject matter presented here.

Hereinafter, exemplary embodiments of the present disclosure will be described with reference to the accompanying drawings. Equal or equivalent components, members, and processes in each of the drawings will be denoted by the same symbols, and overlapping descriptions thereof will be appropriately omitted. Further, the exemplary embodiment is not intended to limit the present disclosure thereto, but is illustrative of the present disclosure. All the features described in the exemplary embodiment or combinations thereof are not necessarily essential for the present disclosure.

In the present specification, "a state in which member A is connected with member B" includes a case where the members A and B are indirectly connected with each other without substantially affecting the electrical connecting state therebetween, a case where the members A and B are indirectly connected with each other without impairing a function or effect to be exhibited by a combination of these members, and a case where the members A and B are indirectly connected with each other via other members, in addition to a case where the members A and B are physically directly connected with each other.

Similarly, "a state in which member C is installed between member A and member B" includes a case where the members C and A or the members C and B are indirectly connected with each other without substantially affecting the electrical connecting state therebetween, a case where the members C and A or the members C and B are indirectly connected with each other without impairing a function or effect to be exhibited by a combination of these members, and a case where the members C and A or the members C and B are indirectly connected with each other via other members, in addition to a case where the members A and C or the members B and C are directly connected with each other.

Also, in the present specification, symbols denoted for electrical signals such as voltage signals and current signals, or circuit elements such as resistors and capacitors may indicate a voltage value, a current value, a resistor value, or a capacity value of each of them.

FIG. 2 is a block diagram of an illumination device 100 including a lighting circuit 200 according to an exemplary embodiment. The illumination device 100 includes a light source 102 and a lighting circuit 200. The light source 102 is a semiconductor light source such as an LED, an LD, or an organic EL, and emits light with a luminance corresponding to a supplied driving current (a forward current) I_F . Further, the light source 102 may be an LED bar including a plurality of LEDs connected in series. The lighting circuit 200 generates a driving current I_{DRV} stabilized to a constant current (target current), supplies the driving current I_{DRV} to the light source 102 in a period in which the light source 102 is to be turned on, and suppresses the current flowing to the light source 102 to be equal to or less than a lighting threshold value in a period in which the light source 102 is to be turned off.

The lighting circuit 200 includes a driving circuit 202 and a clamp circuit 210. The clamp circuit 210 clamps the voltage V_F between both ends of the light source 102 in a period in which the light source 102 is to be turned off. The clamp level V_{CL} is defined to be higher than zero and lower than the threshold voltage V_{TH} of the light source 102 when the light source 102 is turned on/off. More specifically, the

clamp circuit 210 is configured such that enabling (activating) and disabling (deactivating) may be switched in response to a control signal S_1 that instructs the light source 102 to be turned on/off. The control signal S_1 may be generated inside the lighting circuit 200, or may be provided from the outside.

When the control signal S_1 is at a first level (lighting level), the clamp circuit 210 becomes disabled and is in a state where the light source 102 and the driving circuit 202 are not electrically operated. In the disabled state, the clamp circuit 210 may be in a high impedance state.

When the control signal S_1 is at a second level (extinguishing level), the clamp circuit 210 becomes an enabled state and clamps the voltage V_F between both ends of the light source 102 to the clamp level V_{CL} . This is called a first function.

FIG. 3 is a view illustrating I/V characteristics of the light source 102. The horizontal axis represents the voltage between both ends of the light source 102, that is, a forward voltage V_F , and the vertical axis represents a forward current I_F . In a case where the light source 102 is an LED, it may be assumed that in a region where the forward voltage V_F is lower than an on-voltage V_{ON} , the forward current I_F is substantially zero, and the light source 102 is turned off. In a region where the forward voltage V_F is higher than the on-voltage V_{ON} , the forward current I_F increases according to the forward voltage V_F , and the light source 102 emits light with a luminance according to the forward current I_F . Thus, when the light source 102 is an LED, the threshold voltage V_{TH} may be associated with the on-voltage V_{ON} .

Further, the threshold voltage V_{TH} is a boundary between the on state and the off state of the light source 102, and the off state does not require that photons emitted from the light source 102 are completely zero. For example, when the amount of light from the light source 102 is subjected to a multi-level control, a state in which the amount of emitted photons is sufficiently smaller than a light amount corresponding to 1 LSB may be regarded as an off state. Alternatively, a state in which the amount of emitted photons is less than the light amount that may be perceived by humans may be regarded as an off state.

In FIG. 3, when V_{ON} is equal to V_{TH} , the clamp level V_{CL} is set between 0 V and the on-voltage V_{ON} .

A configuration of the lighting circuit 200 has been described above. Next, an operation of the lighting circuit 200 will be described. FIG. 4 is an operation waveform diagram of the lighting circuit 200 of FIG. 2. Before time t_0 , a control signal S_1 is at a lighting level (high level), and the clamp circuit 210 is in a disabled state (DIS). At this time, the forward current I_F of the light source 102 becomes equal to the driving current I_{DRV} generated by the driving circuit 202, and the light source 102 emits light having a luminance according to the driving current I_{DRV} . The forward voltage V_F is the voltage level V_{ON} corresponding to the driving current I_{DRV} .

When the control signal S_1 shifts to the extinguishing level (low level) at time t_0 , the clamp circuit 210 becomes the enabled state (EN). When the clamp circuit 210 becomes the enabled state, the voltage between both ends of the light source 102 (forward voltage) V_F is clamped to the clamp level V_{CL} . The forward voltage V_F decreases toward the clamp level V_{CL} at a predetermined slope by the operation delay of the clamp circuit 210, and the forward current I_F of the light source, that is, the luminance, also decreases with time. It is to be noted that the difference between the driving current I_{DRV} generated by the light source 102 and the forward current I_F flows in the clamp circuit 210.

When the forward voltage V_F crosses the threshold voltage V_{TH} at time t_1 , the forward current I_F becomes zero and the light source 102 is turned off. Thereafter, the forward voltage V_F reaches the clamp level V_{CL} at time t_2 , and then the same voltage level is maintained.

When the control signal S_1 shifts to the lighting level (high level) at time t_3 , the clamp circuit 210 becomes the disabled state (DIS). When the clamp circuit 210 becomes the disabled state, the clamp of the forward voltage V_F of the light source 102 is released, the driving current I_{DRV} flowing in the clamp circuit 210 in the extinguishing period flows to the light source 102, and the forward voltage V_F increases toward the original voltage level V_{ON} . Between time t_3 and time t_4 when a relation of $V_{CL} < V_F < V_{TH}$ is satisfied, the forward current I_F is substantially zero, and the light source 102 is turned off.

After time t_4 at which the forward voltage V_F crosses the threshold voltage V_{TH} , the forward current I_F starts to flow and the luminance of the light source 102 increases. At time t_5 , all of the driving current I_{DRV} flows to the light source 102, and the forward current I_F becomes equal to the driving current I_{DRV} .

A configuration of a lighting circuit 200 has been described above. The advantage of the lighting circuit 200 is clarified when compared to the lighting circuit 1100 of FIG. 1. FIG. 5 is an operation waveform diagram of the lighting circuit 1100 of FIG. 1.

Before time t_{10} , the control signal S_1 is at a lighting level (high level) and a bypass switch 1104 is turned off. The driving current I_{DRV} generated by the driving circuit 202 flows to a light source 1002, and the light source 1002 emits light with a luminance according to the driving current I_{DRV} . The forward voltage V_F is the voltage level V_{ON} corresponding to the driving current I_{DRV} .

When the control signal S_1 shifts to the extinguishing level (low level) at time t_{10} , the bypass switch 1104 is turned on. As a result, the driving current I_{DRV} which flows to the light source 1002 at that time flows to the bypass switch 1104, and the forward current I_F decreases.

When the forward voltage V_F crosses the threshold voltage V_{TH} at time t_{11} , the forward current I_F becomes zero and the light source 1002 is turned off. Thereafter, the forward voltage V_F is lowered to zero (0 V) at time t_{12} .

When the control signal S_1 shifts to the lighting level (high level) at time t_{13} , the bypass switch 1104 is turned off. The driving current I_{DRV} flowing to the bypass switch 1104 in the extinguishing period flows to the light source 1102, and the forward voltage V_F increases toward the original voltage level V_{ON} . Between time t_{13} and time t_{14} when a relation of $0 < V_F < V_{TH}$ is satisfied, the forward current I_F is substantially zero, and the light source 1002 is turned off.

After time t_{14} when the forward voltage V_F crosses the threshold voltage V_{TH} , the forward current I_F starts to flow and the luminance of the light source 1102 increases. In addition, at time t_{15} , all of the driving current I_{DRV} flows to the light source 1002, and the forward current I_F becomes equal to the driving current I_{DRV} .

A configuration of a lighting circuit 1100 of FIG. 1 has been described above. In the lighting circuit 1100 of FIG. 1, in a period τ_0 from time t_{13} at which the control signal S_1 has shifted to the lighting level to time t_{14} at which the forward voltage V_F reaches the threshold voltage V_{TH} (referred to as a lighting disable period), the forward current I_F is zero and the light source 1002 is not able to be turned on.

As the period of the control signal S_1 (switching period T_P) becomes shorter, in other words, as the switching frequency becomes higher, the ratio occupied by the lighting

disable period τ_0 in the period T_P becomes higher. In other words, the switching period T_P is constrained by the lighting disable period τ_0 .

Further, the length of the lighting disable period τ_0 in FIG. 5 may be approximated to $\tau_0 = V_{TH}/SR_0$ by using the rising speed of the forward voltage V_F (slew rate SR_0).

Return to FIG. 4. In FIG. 4, the period between time t_3 and time t_4 corresponds to the lighting disable period τ_1 . The length of the lighting disable period τ_1 may be approximated to $\tau_1 = (V_{TH} - V_{CL})/SR_1$ by using the rising speed of the forward voltage V_F (slew rate SR_1). Assuming that the slew rates of FIGS. 4 and 5 are the same ($SR_0 = SR_1$), the lighting disable period τ_1 of FIG. 4 becomes shorter than the lighting disable period τ_0 of FIG. 5.

Thus, according to the lighting circuit 200 of FIG. 2, since the lighting disable period τ in which the light source 102 is switched from off to on may be shortened, high-speed switching becomes possible.

In addition, since the load fluctuation when viewed from the driving circuit 202 may be reduced, the design restriction of the driving circuit 202 may be alleviated, thereby facilitating the design of the driving circuit 202.

For example, the driving circuit 202 may be configured with a switching converter (switch mode power supply) the output current of which is subjected to a constant current control. A switching converter that outputs a constant current is required to have a function of maintaining the output current regardless of a variation in the output voltage. In an application where the output voltage changes at high speed and large amplitude, a response speed required for the switching converter becomes very fast, which makes the design very difficult. The first function of the clamp circuit 210 has an advantage in that the fluctuation range of the output voltage becomes smaller, so that the design of the switching converter is facilitated. The driving circuit 202 may be configured with a linear power supply, but the same advantage may be obtained even in this case.

The lighting disable period τ_1 becomes shorter as the variation width $\Delta V (=V_{TH} - V_{CL})$ of the forward voltage V_F in the extinguishing period and the lighting period is reduced. Thus, in order to increase the switching frequency, the clamp level V_{TH} may be set to be as high as possible in a range not exceeding the threshold voltage V_{TH} . From this point of view, the clamp level V_{CL} may be higher than $\frac{1}{3}$ of the threshold voltage V_{TH} and higher than $\frac{1}{2}$ of the threshold voltage V_{TH} .

In the meantime, when the clamp level V_{CL} is increased too much, the light source 102 may be erroneously turned on in the extinguishing period due to unevenness in the threshold voltage V_{TH} or temperature fluctuation. From this point of view, the clamp level V_{CL} may be lower than $\frac{4}{5}$ of the threshold voltage V_{TH} and lower than $\frac{3}{4}$ of the threshold voltage V_{TH} .

Subsequently, a more preferable function (second function) of the clamp circuit 210 will be described. The clamp circuit 210 immediately reduces the voltage V_F between both ends of the light source 102 to substantially zero in response to the extinguishing instruction of the light source 102 (i.e., a negative edge of the control signal S_1). The clamp circuit 210 then clamps the voltage V_F between both ends of the light source 102 to the clamp level V_{CL} before the light source 102 is turned on (first function).

FIG. 6 is an operation waveform diagram of the lighting circuit including a second function. When the control signal S_1 is switched to the extinguishing level at time t_0 , the

voltage V_F between the both ends of the light source 102 is lowered to zero (0 V). As a result, the forward current I_F is immediately lowered to zero.

Thereafter, the voltage V_F between the both ends of the light source 102 is returned to the clamp level V_{CL} at time t_2 preceding time t_3 at which the control signal S_1 is switched to the lighting level.

Thus, according to the clamp circuit 210 including the second function, the light source 102 may be turned off at high speed.

The present disclosure is not limited to a specific configuration, which is applied to various devices and circuits that are understood as a block diagram or a circuit diagram of FIG. 2 or derived from the above description. Hereinafter, in order to facilitate understanding of the nature of the present disclosure and the circuit operation, and to clarify these, rather than narrowing the scope of the present disclosure, a more specific configuration example or modification example will be described.

First Configuration Example

FIG. 7 is a circuit diagram of a first configuration example 200A of a lighting circuit 200 of FIG. 2. A clamp circuit 210A includes the above-described first function. The clamp circuit 210A includes a first switch SW_1 and a clamp resistor 214 provided in series on a first path 212 that is in parallel with the light source 102. The on state of the first switch SW_1 corresponds to the enabled state of the clamp circuit 210A, and the off state of the first switch SW_1 corresponds to the disabled state of the clamp circuit 210A.

When the resistance value of the first path 212 is R_1 and the driving current generated by the driving current 202 is I_{DRV} , the voltage between both ends of the first path 212 becomes $R_1 \times I_{DRV}$ in an enabled state. In other words, the clamp level V_{CL} is given by the following equation.

$$V_{CL} = R_1 \times I_{DRV}$$

Therefore, a relation of $0 < R_1 \times I_{DRV} < V_{TH}$ may be satisfied.

The resistance value R_1 of the first path 212 is the sum of the resistance value of the clamp resistor 214 and the resistance value of the first switch SW_1 .

The clamp circuit 210A may further include a controller 220. The controller 220 controls the on/off of the first switch SW_1 based on the control signal S_1 . Specifically, the controller 220 turns off the first switch SW_1 when the control signal S_1 is at a lighting level, and turns on the first switch SW_1 when the control signal S_1 is at an extinguishing level.

According to the lighting circuit 200A of FIG. 7, the operation of FIG. 4 may be implemented.

Second Configuration Example

FIG. 8 is a circuit diagram of a second configuration example 200B of the lighting circuit 200 of FIG. 2. A clamp circuit 210B includes the above-described first function and second function. The clamp circuit 210B further includes a second switch SW_2 provided on the second path 216 that is in parallel with the light source 102, in addition to the clamp circuit 210A of FIG. 7.

The controller 220 turns on the first switch SW_1 in the extinguishing period of the light source 102 (the control signal S_1 is at the extinguishing level), and turns off the first switch SW_1 in the lighting period of the light source 102 (the control signal S_1 is at the lighting level). Further, the controller 220 turns on the second switch SW_2 immediately after the extinguishing instruction of the light source 102

(i.e., an edge corresponding to the control signal S_1) is triggered, and then turns off the second switch SW_2 before the lighting instruction of the light source **102**. For example, when the lighting level is high, the controller **220** may turn on the second switch SW_2 for a very short time with the negative edge of the control signal S_1 as a trigger. Alternatively, the controller **220** may turn on the second switch SW_2 for a predetermined period of time from the negative edge of the control signal S_1 .

According to the lighting circuit **200B** of FIG. 8, the operation of FIG. 5 may be implemented.

FIGS. 9A and 9B are circuit diagrams illustrating a specific configuration example of a clamp circuit **210B** of FIG. 8. Each of the first switch SW_1 and the second switch SW_2 is an N-channel metal oxide semiconductor field effect transistor (MOSFET). Further, the first switch SW_1 and the second switch SW_2 may be configured with a bipolar transistor or an insulated gate bipolar transistor (IGBT).

Reference is made to FIG. 9A. $\#S_1$ is an inverted signal of the control signal S_1 in which the extinguishing level is high and the lighting level is low. A first driver **222** drives the first switch SW_1 based on the control signal $\#S_1$. A differentiator **226** differentiates the control signal S_1 . For example, the differentiator **226** may be configured with a high pass filter, and, for example, may include a capacitor provided on a signal path. The output of the differentiator **226** is increased by the positive edge of the control signal $\#S_1$ and immediately returns to zero. A second driver **224** drives the second switch SW_2 based on the output of the differentiator **226**.

In FIG. 9A, the differentiator **226** and the second driver **224** may be replaced with each other. Further, in FIG. 9A, the second driver **224** may be omitted, the output of the first driver **222** may be directly supplied to a gate of the first switch SW_1 , and the output of the first driver **222** may be supplied to a gate of the second switch SW_2 via the differentiator **226**.

Reference is made to FIG. 9B. The first driver **223** drives the first switch SW_1 based on the control signal S_1 . An edge detector **228** detects an edge corresponding to the extinguishing instruction of the control signal S_1 (a positive edge when the extinguishing level is low), and generates an edge detection signal S_2 that is at a high level for a predetermined time from the detected edge. The second driver **224** drives the second switch SW_2 based on the edge detection signal S_2 .

FIGS. 10A to 10E are circuit diagrams illustrating modifications of the clamp circuit **210**. Here, only a portion related to the first function is illustrated. In the clamp circuit **210** of FIG. 10A, the clamp resistor is omitted and a MOSFET having a large on-resistance R_{ON} corresponding to the resistance of the clamp resistor may be used as the first switch SW_1 . That is, the on-resistance R_{ON} becomes the resistance value R_1 of the first path **212**, and a numerical value obtained by a relation of $R_{ON} \times I_{DRV}$ becomes the clamp level V_{CL} .

In the clamp circuit **210** of FIG. 10B, a diode **215** and a first switch SW_1 are provided in series on the first path **212**. The driving current I_{DRV} flows through the diode **215** to generate a substantially constant forward voltage V_c . When the on-resistance of the first switch SW_1 is sufficiently small, V_{CL} becomes equal to V_c . When the on-resistance of the first switch SW_1 is sufficiently large, a relation of $V_{CL} = V_c + I_{DRV} \times R_{ON}$ is satisfied.

In the clamp circuit **210** of FIG. 10C, a Zener diode **217** and a first switch SW_1 are provided in series on the first path **212**. The driving current I_{DRV} flows through the Zener diode **217** to generate a substantially constant Zener voltage V_Z . When the on-resistance of the first switch SW_1 is sufficiently

small, V_{CL} becomes equal to V_Z . When the on-resistance of the first switch SW_1 is large, a relation of $V_{CL} = V_Z I_{DRV} \times R_{ON}$ is satisfied.

In the clamp circuit **210** of FIG. 10D, when the resistance value of the clamp resistor **214** is R_1 , a relation of $V_{CL} = V_c + (R_1 + R_{ON}) \times I_{DRV}$ is satisfied. In the clamp circuit **210** of FIG. 10E, when the resistance value of the clamp resistor **214** is R_1 , a relation of $V_{CL} = V_Z + (R_1 + R_{ON}) \times I_{DRV}$ is satisfied.

In sum, the clamp circuit **210** may be configured with any combination of a resistor, a diode, and a Zener diode.

Third Configuration Example

FIG. 11 is a circuit diagram of a third configuration example 200C of the lighting circuit **200** of FIG. 2. The clamp circuit **210C** includes the above-described first function and second function. The clamp circuit **210C** includes a shaft transistor M_3 provided on the first path **212** in parallel with the light source **102**, and a transistor control circuit **230**. The transistor control circuit **230** sets the voltage (gate voltage, base voltage) V_{CNT} of the control terminal of the shaft transistor M_3 so that the voltage between both ends of the light source **102** becomes a clamp level defined to be lower than the threshold voltage V_{TH} when the light source **102** is turned on/off, when the control signal S_1 is at the extinguishing level, that is, in the enabled state of the clamp circuit **210C**. The shaft transistor M_3 may be a MOSFET, a bipolar transistor, or an IGBT. The transistor control circuit **230** turns off the shaft transistor M_3 when the control signal S_1 is at the lighting level, that is, in the disabled state of the clamp circuit **210C**.

FIG. 12 is a circuit diagram illustrating a first configuration example of the clamp circuit **210C** of FIG. 11. The transistor control circuit **230** of FIG. 12 includes a feedback circuit **232**, a third switch SW_3 , and a fourth switch SW_4 .

The feedback circuit **232** receives a target voltage V_{REF} of the clamp level and a feedback voltage V_{FB} representing a voltage between both ends of the shaft transistor M_3 , and brings the voltage V_F between both ends of the light source **102** closer to the clamp level V_{CL} by feedback. The configuration of the feedback circuit **232** is not limited thereto, but may be configured with an analog error amplifier or may be configured with a digital feedback circuit (a PI controller or a PID controller) and an A/D converter. The feedback circuit **232** and the shaft transistor M_3 may be understood as a shaft regulator.

The third switch SW_3 is provided between the control terminal (gate) of the shaft transistor M_3 and a low voltage terminal **233** to which a predetermined low voltage V_L is supplied. Further, the third switch SW_3 may be provided between the control terminal (gate) of the shaft transistor M_3 and a low potential side end (cathode) of the light source **102**, as illustrated in FIG. 14.

The fourth switch SW_4 is provided between the control terminal (gate) of the shaft transistor M_3 and a high voltage terminal **234** to which a predetermined high voltage V_H is supplied. Further, the fourth switch SW_4 may be provided between the control terminal (gate) of the shaft transistor M_3 and a high potential side end (anode) of the light source **102**, as illustrated in FIG. 14.

The control signal S_1 includes a signal S_{1A} instructing on/off of the feedback circuit **232**, a signal S_{1B} instructing on/off of the third switch SW_3 , and a signal S_{1C} instructing on/off of the fourth switch SW_4 . The feedback circuit **232** is configured to be in the enabled state when the signal S_{1A} is at a high level and in the disabled state when the signal S_{1A} is at a low level.

FIG. 13 is an operation waveform diagram of the clamp circuit 210C of FIG. 12. Before time t_0 , the control signal S_1 is at a lighting level (high level). Specifically, the control signals S_{1A} , S_{1B} , and S_{1C} are generated such that the feedback circuit 232 is in the disabled state, the third switch SW_3 is in the on state, and the fourth switch SW_4 is in the off state. As a result, the gate voltage V_{CNT} of the shaft transistor M_3 becomes a low voltage V_L , and the shaft transistor M_3 is turned off. This corresponds to the disabled state (DIS) of the clamp circuit 210C. At this time, the forward current I_F of the light source 102 becomes equal to the driving current I_{DRV} generated by the driving circuit 202, and the light source 102 emits light with a luminance corresponding to the driving current I_{DRV} . The forward voltage V_F is the voltage level V_{ON} corresponding to the driving current I_{DRV} .

The control signal S_1 shifts to the extinguishing level (low level) at time t_0 . The control signals S_{1A} , S_{1B} , and S_{1C} are generated so that the feedback circuit 232 is in the disabled state, the third switch SW_3 is in the off state, and the fourth switch SW_4 is in the on state. As a result, the gate voltage V_{CNT} of the shaft transistor M_3 is immediately changed to a high voltage V_H , and the shaft transistor M_3 is turned on. Therefore, the forward current I_F is immediately lowered to zero and the light source 102 is turned off.

At subsequent time t_2 , the control signals S_{1A} , S_{1B} , and S_{1C} are generated so that the feedback circuit 232 is in the enabled state, the third switch SW_3 is in the off state, and the fourth switch SW_4 is in the off state. The gate voltage V_{CNT} is adjusted by the feedback control of the feedback circuit 232 so that the voltage V_F between both ends of the light source 102 is close to the clamp level V_{CL} .

The control signal S_1 shifts to the lighting level (high level) at time t_3 . The control signals S_{1A} , S_{1B} , and S_{1C} are generated such that the feedback circuit 232 is in the disabled state, the third switch SW_3 is in the on state, and the fourth switch SW_4 is in the off state. By turning on the third switch SW_3 , the shaft transistor M_3 is turned off, the clamp of the forward voltage V_F of the light source 102 is released, the driving current I_{DRV} flowing through the shaft transistor M_3 in the extinguishing period flows to the light source 102, and the forward voltage V_F increases toward the original voltage level V_{ON} .

After time t_4 when the forward voltage V_F crosses the threshold voltage V_{TH} , the forward current I_F starts to flow and the luminance of the light source 102 increases. At time t_5 , all of the driving current I_{DRV} flows to the light source 102, and the forward current I_F becomes equal to the driving current I_{DRV} .

The operation of the clamp circuit 210C of FIG. 12 has been described above. According to the clamp circuit 210C, the above-described first function and second function may be implemented.

Further, in FIG. 12, the fourth switch SW_4 may be omitted when the transistor control circuit 230 may shift the output voltage V_{CNT} to the high voltage V_H at high speed. In addition, the third switch SW_3 may be omitted when the transistor control circuit 230 may shift the output voltage V_{CNT} to the low voltage V_L at high speed.

FIG. 14 is a circuit diagram illustrating a second configuration example of the clamp circuit 210C of FIG. 11. The clamp circuit 210C of FIG. 14 includes a constant voltage circuit 236 instead of the feedback circuit 232. The constant voltage circuit 236 is provided between the control terminal (gate) of the shaft transistor M_3 and the high potential side end (drain), and maintains the voltage between the gate and the drain of the shaft transistor M_3 at a constant level. However, since the capacity of the constant voltage circuit

236 is lower than the capacities of the third switch SW_3 and the fourth switch SW_4 , and the operation of the constant voltage circuit 236 may not be seen when either the third switch SW_3 or the fourth switch SW_4 is turned on.

5 The configuration of the constant voltage circuit 236 is not particularly limited, but, for example, may include a plurality of (n) diodes connected in series and a resistor. In this case, the clamp level V_{CL} satisfies a relation of $V_{CL} = (V_{th(gs)} + V_{fN} + V_R)$. V_f is the forward voltage of the diode and $V_{th(gs)}$ is the threshold voltage between the gate and the source of the shaft transistor M_3 .

10 In FIG. 14, the high voltage V_H is the anode voltage of the light source 102 (the drain voltage of the shaft transistor M_3), and the low voltage V_L is the cathode voltage of the light source 102 (the source voltage of the shaft transistor M_3). Further, as illustrated in FIG. 12, the high voltage V_H may be an arbitrary predetermined voltage and the low voltage V_L may be grounded.

15 Subsequently, the operation of the clamp circuit 210C of FIG. 14 will be described above. The operation waveform diagram is the same as that illustrated in FIG. 13, in which the control signal S_{1A} is ignored. According to the clamp circuit 210C of FIG. 14, the same effect as the clamp circuit 210C of FIG. 12 is obtained.

Use

20 Subsequently, the use of a lighting circuit 200 will be described. The illumination device 100 of FIG. 2 may be used as a vehicular lamp. FIGS. 15A to 15D are views illustrating a vehicular lamp including a lighting circuit 200. A vehicular lamp 300A of FIG. 15A is a scanning lamp that scans the light emitted from the light source 302. The vehicular lamp 300A includes a lighting circuit 200, a light source 302, and a scanning device 304. The scanning device 304 includes a motor and a reflector (blade). The light emitted from the light source 302 is reflected by the blade and scanned ahead of the vehicle. An arbitrary light distribution pattern may be implemented or a road surface may be drawn by dimming the light emitted from the light source 302 in synchronization with the periodic motion of the blade or by switching the emitted light at high speed.

25 The vehicular lamp 300B of FIG. 15B is a scanning lamp that scans the light emitted from the light source 302. The vehicular lamp 300B includes the lighting circuit 200, the light source 302, and a scanning device 306. The scanning device 306 includes a motor and a galvano mirror.

30 The vehicular lamp 300C of FIG. 15C includes a lighting circuit 200, a light source 302, and a pattern forming device 308. The pattern forming device 308 is a digital mirror device (DMD) including a plurality of pixels. Each pixel of the DMD may be individually turned on/off. The light emitted from the light source 302 is reflected by the pattern forming device 308, and the reflected light has a pattern corresponding to the state of the pixel of the DMD.

35 The vehicular lamp 300D of FIG. 15D includes a lighting circuit 200, a light source 302, and an actuator 310 that controls the direction of the light source 302. The light emitted from the light source 302 may be scanned by periodically changing the direction of the light source 302 by the actuator 302.

40 FIGS. 16A and 16B are circuit diagrams of the vehicular lamp including a lighting circuit 200. The vehicular lamp 300E of FIG. 16A includes a first light source 312, a second light source 314, and the lighting circuit 200. For example, the first light source 312 is a low beam, and the second light source 314 is a high beam. The lighting circuit 200 includes

a driving circuit 202 and a clamp circuit 210. The second light source 314 corresponds to the above-described light source 102, and the clamp circuit 210 is connected to both ends of the second light source 314.

The vehicular lamp 300F of FIG. 16B includes a plurality of (N) light sources 316_1 to 316_N and a lighting circuit 200. The plurality of light sources 316 irradiate different positions in front of the vehicle. The lighting circuit 200 includes a driving circuit 202 and a plurality of clamp circuits 210_1 to 210_N. Each of the clamp circuits 210 is connected between both ends of the corresponding light source 316_i. A control signal S₁-i that instructs the lighting/extinguishing of the corresponding light source 316_i is input to each of the clamp circuits 210_i.

In the above description, the illumination device 100 having a single light source 102 has been described, but the present disclosure is also applicable to the driving of a plurality of light sources.

FIG. 17 is a block diagram of an illumination device 100D including a plurality of light sources 102. The illumination device 100D includes a plurality of light sources 102_1 to 102_N and a lighting circuit 200D thereof. The light source 102 is, for example, an LED or an LD, and a plurality of light sources 102_1 to 102_N are connected in series.

The lighting circuit 200D includes a plurality of shaft transistors M₃, a driving circuit 202, a plurality of interface circuits 204_1 to 204_N, an oscillator 206, and a microcomputer 208.

Each of the shaft transistors M₃ is connected to both ends of the corresponding light source 102. Further, each of the interface circuits 204 drives the corresponding shaft transistor M₃. The interface circuit 204 corresponds to the clamp circuit 210C of FIG. 11.

The microcomputer 208 is a controller that controls the lighting circuit 200D in an integrated manner, and controls the lighting/extinguishing of each of the plurality of light sources 102_1 to 102_N based on information from ECU on the vehicle side which is not illustrated.

The light source 102_1, the interface circuit 204_1, and the microcomputer 208 are considered. The interface circuit 204 includes a third switch SW₃, a fourth switch SW₄, a regulator 240, and a charge pump 242. The regulator 240 and the microcomputer 208 correspond to the feedback circuit 232 of FIG. 12. That is, the feedback circuit 232 is configured with a digital controller and an analog output unit. The former corresponds to the microcomputer 208 and the latter corresponds to the regulator 240. The microcomputer 208 generates a voltage command value S_{REF} such that the feedback voltage V_{FB} obtained by dividing the drain voltage of the shaft transistor M₃ is fed back and the feedback voltage V_{FB} is close to a target voltage defining the clamp level C_L. The regulator 240 generates the control voltage V_{CNT} corresponding to the voltage command value S_{REF} at the control terminal of the shaft transistor M₃. The charge pump 242 receives a clock signal from the oscillator 206, performs a boost operation, and generates a high voltage V_H.

According to this illumination device 100D, a plurality of light sources 102_1 to 102_N may be independently controlled. The interface circuit 204 may be configured with the above-described arbitrary clamp circuit 210.

From the foregoing, it will be appreciated that various exemplary embodiments of the present disclosure have been described herein for purposes of illustration, and that various modifications may be made without departing from the scope and spirit of the present disclosure. Accordingly, the various exemplary embodiments disclosed herein are not

intended to be limiting, with the true scope and spirit being indicated by the following claims.

What is claimed is:

1. A lighting circuit of a light source, comprising:
a driving circuit configured to generate a driving current to be supplied to the light source; and

a clamp circuit configured to receive an input signal oscillating between an on signal and an off signal, wherein the clamp circuit is further configured (i) to be enabled to clamp a voltage between both ends of the light source to a clamp level which is defined to be higher than zero and lower than a threshold voltage of turning-on/off of the light source in a first period when the input signal is the off signal, and (ii) to be disabled to apply substantially an entire amount of the driving current to the light source in a second period when the input signal is the on signal.

2. The lighting circuit of claim 1, wherein, in response to an extinguishing instruction of the light source, the clamp circuit immediately reduces the voltage between the both ends of the light source to zero, and then clamps the voltage to the clamp level.

3. The lighting circuit of claim 1, wherein the clamp circuit includes a first switch and a clamp resistor provided in series on a first path that is in parallel with the light source, and

when a resistance value of the first path is R₁, the threshold voltage of the light source is V_{TH}, and the driving current is IDR_V, a relation of $0 < R_1 \times IDR_V < V_{TH}$ is satisfied.

4. The lighting circuit of claim 1, wherein the clamp circuit includes a first switch provided on a first path in parallel with the light source, and

when a resistance value of the first path is R₁, the threshold voltage of the light source is V_{TH}, and the driving current is IDR_V, a relation of $0 < R_1 \times IDR_V < V_{TH}$ is satisfied.

5. The lighting circuit of claim 1, wherein the clamp circuit further includes a second switch provided on a second path that is in parallel with the light source, and the second switch is turned on immediately after an extinguishing instruction of the light source, and is turned off before a lighting instruction of the light source.

6. The lighting circuit of claim 1, wherein the clamp circuit further includes:

a shaft transistor provided between the both ends of the light source; and
a transistor control circuit configured to generate a voltage of a control terminal of the shaft transistor such that a voltage between the both ends of the light source becomes the clamp level in a period in which the light source is to be turned off.

7. The lighting circuit of claim 6, wherein the transistor control circuit includes a feedback circuit which brings the voltage between the both ends of the light source close to the clamp level by feedback.

8. The lighting circuit of claim 6, wherein the transistor control circuit includes a constant voltage circuit provided between the control terminal of the shaft transistor and a high potential side end.

9. The lighting circuit of claim 6, wherein the transistor control circuit further includes a third switch provided between the control terminal of the shaft transistor and a low potential side end of the light source, or between the control terminal of the shaft transistor and a low voltage terminal to which a predetermined low voltage is supplied.

15

10. The lighting circuit of claim **6**, wherein the transistor control circuit further includes a fourth switch provided between the control terminal of the shaft transistor and a high potential side end of the light source, or between the control terminal of the shaft transistor and a high voltage terminal to which a predetermined high voltage is supplied.

11. A lighting circuit of a light source, comprising:
 a driving circuit configured to generate a driving current to be supplied to the light source;
 a first switch and a clamp resistor provided in series on a first path that is in parallel with the light source;
 a second switch provided on a second path that is in parallel with the light source and the first path; and
 a controller configured to control the first switch and the second switch such that, the controller provides an input signal oscillating between an on signal and an off signal,
 wherein the controller is further configured to (i) turn on the first switch to clamp a voltage between both ends of the light source to a clamp level which is defined to be higher than zero and lower than a threshold voltage of

5

10

15

20

16

turning-on/off of the light source in a first period when the input signal is the off signal, and (ii) to turn off the first switch to apply substantially an entire amount of the driving current to the light source in a second period when the input signal is the on signal.

12. The lighting circuit of claim **11**, wherein the controller turns on the first switch in an extinguishing period of the light source and turns off the first switch in a lighting period of the light source, and

the controller turns on the second switch immediately in response to an extinguishing instruction of the light source, and turns off the second switch before a lighting instruction of the light source.

13. A vehicular lamp comprising:
 a light source; and
 the lighting circuit of claim **1** configured to drive the light source.

14. The vehicular lamp of claim **13**, wherein the light sources are plural.
